BARBER SHOP SIGN

Harrison C. Carnell, Detroit, Mich.

Application July 24, 1958, Serial No. 51,927

Term of patent 14 years

(Cl. D1—12)

Fig. 1 is a front elevational view of a barber shop sign showing my new design, the rear being substantially like the front shown and the vertical and horizontal lines on the bands indicating contrasting colors;

Fig. 2 is a top plan view thereof, the bottom being substantially like the top shown;

Fig. 3 is a fragmentary top plan view thereof with portions broken away to show the configuration of the ribs; and,

Fig. 4 is an end elevational view thereof, the opposite end being substantially like the end shown.

The dominant features of my design reside in the full line portions of the drawing.

I claim:

The ornamental design for a barber shop sign, substantially as shown and described.
